US00D980262S

(12) **United States Design Patent** (10) **Patent No.:** **US D980,262 S**
Li (45) **Date of Patent:** **** Mar. 7, 2023**

(54) **DISPLAY SCREEN OR PORTION THEREOF WITH GRAPHICAL USER INTERFACE**

(71) Applicant: **KWAI GAMES PTE. LTD.**, Singapore (SG)

(72) Inventor: **Jingyu Li**, Beijing (CN)

(73) Assignee: **KWAI GAMES PTE. LTD.**, Singapore (SG)

(**) Term: **15 Years**

(21) Appl. No.: **35/512,320**

(22) Filed: **Jul. 22, 2021**

(80) **Hague Agreement Data**

Int. Filing Date: **Jul. 22, 2021**

Int. Reg. No.: **DM/21555**

Int. Reg. Date: **Jul. 22, 2021**

Int. Reg. Pub. Date: **Aug. 6, 2021**

(30) **Foreign Application Priority Data**
